UNITED STATES PATENT OFFICE.

JAMES F. MARTIN, OF PHILADELPHIA, PENNSYLVANIA, ASSIGNOR TO
JOHN B. HALL, OF PHILADELPHIA, PENNSYLVANIA.

HAIR-CRIMPER.

SPECIFICATION forming part of Letters Patent No. 789,041, dated May 2, 1905.

Application filed January 11, 1904. Serial No. 188,442.

To all whom it may concern:

Be it known that I, JAMES F. MARTIN, a citizen of the United States, residing in the city and county of Philadelphia, State of Pennsylvania, have invented a new and useful Improvement in Hair-Crimpers, of which the following is a specification.

My invention relates to a novel construction of a hair-crimper, comprising two or more jaws secured together at one of their ends in such a manner as to be movable with reference to each other, suitable means being provided for connecting or locking the free ends of the jaws, whereby accidental displacement of the jaws in either direction is prevented.

It further consists of novel features of construction, all as will be hereinafter fully set forth.

Figure 1 represents a perspective view of a hair-crimper embodying my invention in open position. Fig. 2 represents a perspective view of the same in closed position. Fig. 3 represents a plan view of a portion of one of the members, showing another form.

Similar numerals of reference indicate corresponding parts in the figures.

Referring to the drawings, 1 designates a hair crimper or curler, the same consisting of the member 2 and the member 3, which are movably connected together at one of their ends in any suitable manner. In the drawings I have shown an eyelet 4, which connects the said members, whereby they are movable with respect to each other. At the opposite or free end of the member 2 is a reduced neck portion 5, formed by the recesses or cut-away portions 6 in the said member 2. The member 3 is provided with the recesses 7, formed by the projecting portions 8, it being seen that the reduced neck portion 5 is seated in the recess 7 by a proper manipulation of either one of the members, which being formed of resilient material may be sufficiently deflected in a plane substantially at a right angle with that of their relative pivotal movement and the neck 5 placed in position, the

projecting portion 8 occupying the cut-away portions 6. In Fig. 3 I have shown the projections 8 provided with lugs 9 or with a reduced opening to the recess 7, the effect of which is evident, as it forms an additional locking feature for the members, the resiliency thereof permitting the insertion of the neck. I preferably desire to make my members of flat strips, and, if desired, the free end of either of the members can be slightly bent, as shown in the drawings.

It will be understood that the hair is wound around one of the members and the other brought into engagement with said first member. By the interlocking device referred to the two members are prevented or locked against accidental displacement in all directions, the hair being maintained in position between the same.

It will be understood that the interlocking devices may be constructed in slightly-different form and may be elsewhere located than as shown without departing from the spirit of my invention.

It will be evident that various changes may be made by those skilled in the art which may come within the scope of my invention, and I do not, therefore, desire to be limited in every instance to the exact construction herein shown and described.

Having thus described my invention, what I claim as new, and desire to secure by Letters Patent, is—

A hair-crimper comprising members movably connected together at their ends, one of said members being formed at its free end with a recess and projecting portions adjacent thereto, the other member having at its free end a cut-away portion adapted to engage said projections, whereby accidental displacement of the members is prevented.

JAMES F. MARTIN.
